[57] CLAIM

The ornamental design for a hand held signal light for directing aircraft or the like, as shown and described.

DESCRIPTION

FIG. 1 is a front elevational view of the hand held signal light for directing aircraft or the like showing my new design;

FIG. 2 is a rear elevational view thereof;

FIG. 3 is a left side elevational view thereof;

FIG. 4 is a right side elevational view thereof;
FIG. 5 is a top plan view thereof on an enlarged scale;

and,

FIG. 6 is a bottom plan view thereof on an enlarged scale.

FIG. 1

FIG. 2

*FIG. 3**FIG. 4**FIG. 5**FIG. 6*
